US0D1088356S

(12) United States Design Patent (10) Patent No.: US D1,088,356 S
(45) Date of Patent: * Aug. 12, 2025

(54) HELMET

- (71) Applicant: HexArmor, Limited Partnership,
Grand Rapids, MI (US)
- (72) Inventors: Daniel Alejandro García Orellana,
Austin, TX (US); César Antonio Saavedra Monteroso, Guatemala (GT)
- (73) Assignee: HexArmor, Limited Partnership,
Grand Rapids, MI (US)
- () Term: 15 Years
- (21) Appl. No.: 29/909,420
- (22) Filed: Aug. 4, 2023
- (51) LOC (15) Cl. 29-02
- (52) U.S. Cl. USPC D29/102
- (58) Field of Classification Search
USPC D29/102, 103, 107, 106, 105
CPC A42B 3/04; A42B 3/22
See application file for complete search history.

(57) CLAIM

The ornamental design for a helmet as shown and described.

DESCRIPTION

FIG. 1 is a front perspective view of a helmet according to the claimed design;

FIG. 2 is a rear perspective view thereof;

FIG. 3 is a front elevation view thereof;

FIG. 4 is a right side elevation view thereof;

FIG. 5 is a left side elevation view thereof; and,

FIG. 6 is a top plan view thereof.

The portions of the article shown in broken line form no part of the claimed design.

Dash-dot-dash broken lines adjacent un-shaded areas represent bounds of the claimed design and form no part of the claimed design themselves.

1 Claim, 6 Drawing Sheets
